[57] CLAIM

The ornamental design for a pull, as shown and described.

DESCRIPTION

FIG. 1 is a front elevational view of a pull incorporating my new design.

FIG. 2 is a bottom plan view thereof, the top being a mirror image.

FIG. 3 is an end elevational view thereof.

FIG. 4 is an enlarged fragmentary sectional view taken on line 4—4 of FIG. 1.

FIG. 5 is an enlarged sectional view taken on line 5—5 of FIG. 2.

FIG. 6 is an enlarged sectional view similar to FIG. 5 of a second embodiment of the design of FIG. 1, the only difference being the use of a wood covering on the handle portion.

fig. 1.

fig. 2.

fig. 3.

fig. 4.

fig. 5.

fig. 6.
